COMBINED INKWELL AND PENHOLDER

William C. Nein, New York, N. Y.

Application September 25, 1942, Serial No. 459,640

6 Claims. (Cl. 120—63)

1

This invention relates to ink-wells and more particularly to improved closed combined ink-wells and penholders.

The main object of this invention is to provide an improved ink-well and penholder which is a practical device.

Another object of the invention is to provide means operated by the penholder to feed ink from the ink reservoir to the pen.

Referring to the drawings:

Fig. 1 is a sectional elevation of the invention showing the arrangement of the various parts including a suitable supporting base.

Fig. 2 is a top plan view of the flexible diaphragm, part 7, of Fig. 1.

Fig. 3 is a sectional elevation of a modification of the invention as shown in Fig. 1.

Fig. 4 shows a top plan view of a modified form of part 7 as shown in Fig. 3.

Fig. 5 is an elevational view partly in section showing a modified form of the ink-feeding member.

Referring now to the drawings and particularly to Fig. 1, 1 is an openmouthed reservoir, hollow and substantially spherical in form. The open mouth of the reservoir 1 is provided with an externally threaded portion 3—3 to receive a cap or closure 5 which is preferably formed of molded plastic with an inset threaded metal collar 3'. Within the reservoir 1 is fastened a weight 2 which acts as a counterbalance for the various parts as shown. The metal inset 3' is formed with an inwardly projecting flange which overlies the top edge of the threaded collar 3 of the ink reservoir 1. Clamped between this flange and the edge of the collar 3 is the marginal flange of a flexible rubber diaphragm 7. A ring or washer 16 of a width to project inwardly beyond the edge of the flange of the inset 3' is inserted between the margin of the diaphragm and the flange of the insert for a purpose which will be later described. The diaphragm 7, Figs. 1 and 3, is made preferably of a form as shown, and is provided with an opening 18 through which is forced, as an airtight fit, the shank 9 of the pen holding member 10. The shank 9 is provided with a groove 19 to fix the position of diaphragm 7. The shank 9 of the penholding member 10 is preferably circular in form and is provided with a multiple diameter bore 12 which opens into a well 14 at its

2

upper end and in which well 14 and part of the bore 12 is normally mounted the pen 23 of a penholder 11. The penholder 11 rests in the hole 10' of member 10. The penholding member 10 is provided with a shoulder 15 which cooperates with the inwardly projecting edge of washer 16 to limit the downward movement of the pen-holding member 10. By substituting washers of various thickness the extent of movement of the penholding member may be varied. The whole assembly on reservoir 1 is mounted in a supporting base 13, which base has a socket 20 having a portion shaped to fit the contour of the reservoir 1. In this portion a friction lining 17 is provided to control the movement of reservoir 1 as desired.

Beneath the curved portion of the socket 20 which serves as a seat for the spherical reservoir the socket 20 is in the form of a cylindrical well 20'. Member 21 is a knob fastened to reservoir 1 as shown by any suitable means such as a screw 22 or it can be made a part of 1 and acts to limit the movement of the reservoir 1 with respect to the base 13 which is accomplished by the cylindrical wall 20' of the base. The upward movement 25 of member 10 is limited by a ledge 5' of member 5 and the pressure against 5' is supplied by member 7 which is slightly depressed when member 5 is in position.

In Fig. 3 of the drawing I have illustrated a somewhat modified form of diaphragm wherein the interior of the reservoir is vented without providing a vent hole in the diaphragm. As here shown the diaphragm 7 is formed around its central opening with an upwardly turned conical seat 35 18' which fits loosely against a conical shaped portion 9' at the juncture of the well 14 and tubular extension 9 of the pen-holding member. A spring 25 interposed between the lower end of the tubular member 9 and the bottom of the reservoir 40 normally maintains the pen-holding member in its upper position to thus insure a vent to atmosphere which is closed when member 10 is pushed downward against the spring 25. The inwardly turned flange 5' of the cover 5 serves as a stop 45 to limit the upward movement of the pen-holding member under the pressure of the spring 25. In Fig. 3 I have also shown a slightly modified form of pen-receiving cover for the ink-receiving well 14. As here shown the closure consists of a sheet 50 metal cap having a central hole through which

the pen is inserted into the ink-receiving well. With this form of closure pen holders of any size may be used.

In Fig. 5 I have illustrated a modified form of feed plunger 9 to insure getting substantially all of the ink out of the reservoir when the latter is in inclined position. As here shown the plunger 9 is shortened and is provided at its end with an extension of reduced diameter over which is tightly fitted the end of a flexible tube 29 of a length to reach to the bottom of the reservoir when the latter is tilted to the inclined position permitted by the stop 21. The lower end of the flexible tube 29 is provided with a weight 30 which serves to hold the lower end of the tube at the lowermost point in the reservoir.

As can be seen from the several figures the function of shoulders 15 and 16, which can be variables, is to limit the movement of member 10. The function of the vent 4 to atmosphere in the member 7 is to assure a stable air pressure within the reservoir 1 above the ink. As can be readily seen the area of the vent 4 is very small compared to the area of the member 7 which is depressed when the penholder 11 is pushed downwards in operation, so while some air escapes thru the vent 4 the reduction in pressure within the reservoir is not sufficient to affect the practical operation of the device. In the case of Fig. 3 as can be seen there is no escape of air in operation although the effect of a small portion of the stroke of member 10 is lost. The multiple diameter bore 12 of member 9 prevents ink from squirting up against the pen 23 by relieving the pressure as the ink rises in bore 12 when the device is operated. This is a very important practical feature as can be readily seen. The location of the vent 4 in member 7 is preferably as shown in Fig. 1. When the member 10 is depressed causing diaphragm 7 to flex, the flexing takes place in a circular line through the vent 4 closing it as the downward movement increases thereby assisting in increasing the pressure in the reservoir 1 above the ink. The vent 4 permits any changes which may take place in the air pressure within the reservoir above the ink to equalize itself with the atmosphere.

What I claim is:

1. An improved ink well of the reservoir type comprising, a reservoir, an ink pumping element of elastic material extending into the reservoir and having a flexible diaphragm integral therewith at its inner end, said diaphragm provided with a perforation therethrough, a hollow pen holding member mounted within the pumping element and having its inner end extending through said perforation, said pen holding member reciprocable axially to flex the diaphragm and pump ink from the reservoir into the pen holding member, and a valve in the diaphragm open when the diaphragm is at rest to prevent pressure within the reservoir, and closing when the diaphragm is flexed to permit creation of pressure within the reservoir to pump ink into the pen holding member.

2. An improved ink well of the reservoir type comprising, a reservoir for ink or other like fluid, said reservoir provided with an opening in one side thereof, a hollow plunger reciprocably mounted in said opening and having its inner end in cooperative relation to the ink within the reservoir, a resilient bellows capable of buckling under pressure associated with said hollow plunger, a valve passage in said resilient bellows at the buckling point, said passage being normally open,

and closed when the bellows is subjected to pressure from the hollow plunger.

3. The combination with an open top liquid reservoir, a closure for the open top secured to the reservoir and provided with a cylindrical bore, a tubular element having an enlarged cylindrical head portion mounted for reciprocatory movement in the bore and provided with a tubular extension depending from the head into the reservoir, a resilient diaphragm normally of dome shape form secured at its perimeter between the reservoir and the closure and through the crown of which diaphragm the extension projects, said crown portion being distortable by the inward movement of the tubular element from its most dome-like form towards a less domed condition, said diaphragm provided with normally open means for venting the interior of the reservoir both when the diaphragm is in its fully distended dome form and also during the initial part of said inward distorting movement and said diaphragm functioning by reason of its distortability to provide means operably controlled by the movement of the diaphragm as it progresses beyond said initial movement to close said venting means and thus automatically intercept fluid communication between the interior of the reservoir and the outside air whereby the final part of the depressing step acts to create pressure in the reservoir to force liquid in the reservoir up into said tubular element.

4. An ink-well including a base provided in its upper surface with an upwardly facing socket, the upper portion of the socket being a segment of a sphere and the lower portion being substantially cylindrical, a receptacle supported by the base, having an opening in its upper side and having its under surface conforming to said upper portion and mounted thereon for universal articulation and said under surface being provided with a stop depending therefrom into said lower portion of the socket and adapted in its engagement with the wall defining said lower portion to limit the tilting of the receptacle from its normal upright position.

5. An ink-well of the reservoir type comprising a reservoir mounted for movement about a self-contained axis, an ink pumping element extending into the reservoir and including a flexible diaphragm provided with a perforation therethrough, a hollow pen holding member mounted within the pumping element and having a portion thereof extending through said perforation, said pen holding member reciprocable axially to flex the diaphragm and to pump ink from the reservoir into the pen holding member, said diaphragm provided with a normally open valve for venting the reservoir, said valve automatically operable on the depression of the holding member to close the valve, the extreme lower end of said extending portion having a flexible tube providing an inlet to the pen holding member from the reservoir and tending by reason of its flexibility to lower the inlet towards the bottom of the reservoir in all positions of the same.

6. An ink-well including an ink reservoir having an opening, a closure member for the opening, a pumping element having its upper portion guided for reciprocatory movement in the closure, a flexible diaphragm through which said pumping element extends, the lower intake end of said pumping element normally extending into the ink in the reservoir and constituting

a flexible tube, the lower end of which is weighted.
